Primary Examiner — Rosemary K Tarcza*Assistant Examiner* — Leah E Hoeferkamp(74) *Attorney, Agent, or Firm* — Taft Stettinius & Hollister LLP; Stephen F. Rost(57) **CLAIM**

The ornamental design for an adapter fitting, as shown and described.

DESCRIPTION

FIG. 1 is a perspective view of an adapter fitting shown according to the present design;

FIG. 2 is a left side elevation view thereof;

FIG. 3 is a front view thereof;

FIG. 4 is a rear view thereof; and,

FIG. 5 is a cross-sectional view thereof taken along line 5-5 in FIG. 1.

1 Claim, 4 Drawing Sheets(56)
